R. I. ALLSWORTH.
WALL CONSTRUCTION.
APPLICATION FILED APR. 9, 1920.

1,350,633.

Patented Aug. 24, 1920.

UNITED STATES PATENT OFFICE.

ROBERT I. ALLSWORTH, OF NEW YORK, N. Y.

WALL CONSTRUCTION.

1,350,633.

Specification of Letters Patent. Patented Aug. 24, 1920.

Application filed April 9, 1920. Serial No. 372,536.

To all whom it may concern:

Be it known that I, ROBERT I. ALLSWORTH, a citizen of the United States, residing at New York, in the county of New York and State of New York, have invented certain new and useful Improvements in Wall Construction, of which the following is a specification.

My invention relates to a wall construction in which plaster boards are used, the boards being disposed between vertical channel irons extending from the floor to the ceiling, and a coating of plaster being placed on top of the boards when in place.

15 The channel irons which are used in this connection, are channeled on only one face, the opposite face being flat. Therefore, between two vertical irons there is only one slotted face into which the plaster board

20 can be set, and one object of my invention is to provide a metal clip, which can be attached to the channel iron and which will provide on the normally smooth face of the iron a channeled retaining means adapted

25 to receive one edge of the plaster board.

A further object is to provide an end clip which can be attached at the floor and ceiling to the horizontal channel irons and thereby connect the vertical and horizontal

30 irons.

In the drawings forming part of this specification and in which like reference characters indicate like parts in the several views;—

35 Figure 1 is a vertical section of a wall constructed in accordance with my invention.

Fig. 2 is a cross section on the line 2—2, Fig. 1.

40 Fig. 3 is a cross section on the line 3—3, Fig. 1.

Fig. 4 is a perspective view of one of my end clips.

Fig. 5 is a cross section view of one of the end clips shown in Fig. 4.

45 Fig. 6 is a perspective view of one of my side clips.

Fig. 7 is a perspective view of a modification of the side clip shown in Fig. 6.

Referring to the drawings, the numeral 1

50 indicates a series of vertical channel irons in place as a skeleton structure of a wall. 2—2 indicate the horizontal end irons, the upper one being at the ceiling and the lower one at the floor line. End clips 3, shown in

55 Fig. 4, are provided at the junction point of the vertical and horizontal bars, said end

clips comprising an integral structure of sheet metal formed in two sections, one of said sections being disposed at right-angles to the other. Each section has two flanges 60 3^a—3^a depending therefrom, said flanges being adapted to be bent over around the edges 1^a—2^a of the channel irons 1 and 2, thereby rigidly connecting the irons 1 and 2 together.

65 A series of plaster boards 4, are disposed between the vertical irons, one edge of a board being disposed within the channel formed in one face of an iron, and the opposite edge of the board bearing against the 70 smooth face of the next iron. Clips 5, are provided at intervals along each channel iron, said clips comprising a sheet metal structure, shown in Fig. 6, having flanges, 5^a adapted to be bent over and around the 75 edges 1^a of the channel irons. Extending from the opposite face of the clip are flanges 5^b—5^b and between these flanges is disposed the edge of the board.

80 As many of these clips as may be needed may be placed along the height of the irons, and in the partition as shown in Fig. 1, I have provided one clip at each meeting point of the boards and one centrally of each board, but more or less may be placed 85 as required. It is preferable that a small space 4^a be left between the bottom and top edges of adjacent boards so that plaster may form a key therebetween.

85 In the form of my invention shown in 90 Fig. 7, instead of providing several relatively small clips to each board I have provided one continuous clip of the length of the board, so that a practically continuous channel is formed for the reception of the 95 boards.

95 In assembling a wall or partition made in accordance with my invention, I attach to one edge of each plaster board one or more of my clips. I then place the other edge of 100 the board in the channel formed in one face of a channel iron and bring the board into position between the irons. The flanges 5^a of the clips are now bent over to engage the edges of the next channel iron and the board 105 is permanently in place. Such other clips as may be needed can then be placed in position. Plaster is thereupon placed on both sides of the boards, interlocks by means of the slots 4^a, and covers the channel irons 110 forming a finished wall or partition.

It will thus be seen that I have provided a

wall or partition structure that is substantial, readily assembled and that can be made of less width than the former types without any weakness therein due to the lesser width.

5 In the type of wall and partition structure now in use no provision has been made for utilizing the space of the channel irons to hold the plaster board, due to the fact that there was no way by which the board could 10 be held by the smooth face of one channel iron. But with my improved construction this space is used and my clip forms a ready and useful means for holding the edge of the board against the smooth face of one iron.

15 Having thus described my invention what I claim as new and desire to secure by Letters Patent is:—

1. A wall or partition structure comprising a series of spaced vertical channel irons; 20 horizontal end channel irons; clips adapted to connect each vertical iron to the horizontal irons; plaster boards between said irons, and other clips between the edges of said boards and the vertical irons, each of said 25 clips having flanges adapted to embrace and to be bent into engagement with the flanges of said channel irons.

2. A wall or partition structure comprising a series of spaced vertical channel irons; 30 horizontal end channel irons; clips adapted to connect each vertical iron to the horizontal irons; plaster boards between said irons, one edge of each board being disposed in the channeled face of one adjacent vertical 35 iron, and the other edge being engaged by a supporting clip, adapted to abut the smooth face of the succeeding channel iron and engage the same.

3. A wall or partition structure comprising a series of spaced vertical channel irons; 40 horizontal end channel irons; clips connecting said vertical and horizontal irons, said clips comprising an integral structure formed in two right-angled sections, one of 45 said sections being adapted to engage a vertical iron and the other of said sections a horizontal iron.

4. A wall or partition structure comprising a series of spaced vertical channel 50 irons; horizontal end channel irons; clips

connecting said vertical and horizontal irons, said clips comprising an integral structure of sheet material formed into two right-angle sections, each section having two parallel offset flanges adapted to surround and 55 engage the flanges of the iron.

5. A wall or partition structure comprising a series of spaced vertical channel irons; 60 plaster boards between said irons, one edge of each board being disposed within the channel of one adjoining iron, and the opposite edge of said board abutting and being detachably connected to the smooth face of the succeeding iron.

6. A wall or partition structure comprising a series of spaced vertical channel irons; 65 plaster boards between said irons, one edge of each board being disposed within the channel of one adjoining iron, and the opposite edge of said board carrying a clip 70 adapted to abut the smooth face of the succeeding iron and engage the flanges thereof.

7. A wall or partition structure comprising a series of spaced vertical channel irons; 75 plaster boards between said irons, one edge of each board being disposed within the channel of one adjoining iron, and the opposite edge of said board being engaged by a clip, said clip lying adjacent the smooth face of the succeeding iron and having two 80 offset parallel projections engaging the flanges of the iron.

8. A wall or partition structure, comprising a series of spaced vertical channel irons; 85 plaster boards therebetween, one edge of each board being disposed within the channel of one adjoining iron; and clips adapted to support the opposite edge of each board, said clips comprising an integral structure having a flat body portion adapted to lie 90 adjacent the smooth face of the irons, a plurality of parallel flanges at right-angles to said body portion adapted to receive the edge of the plaster board therebetween, and a plurality of other right-angle flanges projecting in the opposite direction and adapted to be bent to embrace and engage the flanges of the iron.

In testimony whereof I affix my signature.
ROBERT I. ALLSWORTH.
